UNITED STATES PATENT OFFICE.

EDWARD POOLE, OF HALIFAX, ENGLAND, ASSIGNOR TO JOSEPH WILD
& CO., OF NEW YORK, N. Y.

DESIGN FOR A CARPET-PATTERN.

Specification forming part of Design No. 5,898, dated June 4, 1872.

To all whom it may concern:

Specification describing a new and original design for a Carpet, invented by EDWARD POOLE, of Halifax, in the county of York, England.

The accompanying photograph fully illustrates my invention.

This invention relates to a new design for carpets or other fabrics, and consists in the new outline and decoration of the succession of figures used thereon. There are two kinds of such figures, one large and one small, both of oval form, or nearly so, with their respective long diameters at right angles to each

other. The larger figure has an outer border of zigzag lines, and within the same successions of S-scrolls, decorated with flowers, as shown. The smaller figure has a mixtilinear outline, and an inner central figure composed of seven narrow sections of the peculiar form shown.

I claim as my invention—

The design for a carpet, as shown.

EDWARD POOLE.
